[57] **CLAIM**

The ornamental design for base for attaching air conditioner support to a roof, as shown and described.

DESCRIPTION

FIG. 1 is a perspective view of a first embodiment of base for attaching air conditioner support to a roof showing my new design;

FIG. 2 is a top plan view thereof;

FIG. 3 is a front elevation view thereof;

FIG. 4 is a right side elevation view thereof;

FIG. 5 is a left side elevation view thereof;

FIG. 6 is a rear elevation view thereof;

FIG. 7 is a bottom plan view thereof;

FIG. 8 is a perspective view of a second embodiment showing my new design;

FIG. 9 is a top plan view thereof;

FIG. 10 is a front elevation view thereof;

FIG. 11 is a right side elevation view thereof;

FIG. 12 is a left side elevation view thereof;

FIG. 13 is a rear elevation view thereof;

FIG. 14 is a bottom plan view thereof;

FIG. 15 is a perspective view of a third embodiment showing my new design;

FIG. 16 is a top plan view thereof;

FIG. 17 is a front elevation view thereof;

FIG. 18 is a right side elevation view thereof;

FIG. 19 is a left side elevation view thereof;

FIG. 20 is a rear elevation view thereof;

FIG. 21 is a bottom plan view thereof;

FIG. 22 is a perspective view of a fourth embodiment showing my new design;

FIG. 23 is a top plan view thereof;

FIG. 24 is a front elevation view thereof;

FIG. 25 is a right side elevation view thereof;

FIG. 26 is a left side elevation view thereof;

FIG. 27 is a rear elevation view thereof; and,

FIG. 28 is a bottom plan view thereof.
